UNITED STATES PATENT OFFICE.

HARRY SHARDLOW, OF LOS ANGELES, CALIFORNIA, ASSIGNOR TO SOLAR LIGHTING FIXTURE CO., OF LOS ANGELES, CALIFORNIA, A CORPORATION OF CALIFORNIA.

DESIGN FOR A LIGHTING FIXTURE.

Application filed May 4, 1927. Serial No. 21,858. Term of patent 3½ years.

To all whom it may concern:

Be it known that I, HARRY SHARDLOW, a citizen of the United States of America, residing at Los Angeles, in the county of Los Angeles and State of California, have invented a new, original, and ornamental Design for Lighting Fixtures, of which the following is a specification, reference being had to the accompanying drawing, forming part thereof.

Figure 1 is a plan view, and

Fig. 2 is an elevation of a lighting fixture, showing my new design. Only a portion of the ornamentation is shown completed, it being understood that the unornamented portion involves a mere repeat of that portion more fully illustrated. I claim: The ornamental design for a lighting fixture, as shown.

HARRY SHARDLOW.
